Attorney

UNITED STATES PATENT OFFICE.

MARTIN PATREMIO, OF LODI, NEW JERSEY.

CELLULOID BUTTON.

1,382,739.

Specification of Letters Patent. Patented June 28, 1921.

Application filed February 8, 1921. Serial No. 443,369.

To all whom it may concern:

Be it known that I, MARTIN PATREMIO, a citizen of the United States, residing at Lodi, in the county of Bergen and State of 5 New Jersey, have invented certain new and useful Improvements in Celluloid Buttons, of which the following is a full, clear, and exact specification.

This invention relates to buttons and has 10 for its object to simplify and improve the construction of buttons made of celluloid or other similar materials. A special object is to provide improved means for ornamenting such buttons and at the same time reinforcing or strengthening them.

The invention contemplates the formation of a button with a recess in its face to receive an ornamented panel. The ornamentation on the panel may be widely varied, and 20 in assembling the panels and buttons, a panel bearing any desired decoration may be selected to go with each button. Furthermore, the panel is preferably provided with a flange at its edge to engage the walls 25 of the recess in the button so as to reinforce and strengthen the button structure.

The invention will be first hereinafter described in connection with the accompanying drawings, which constitute part of this 30 specification, and then more specifically defined in the claims at the end of the description.

In the accompanying drawings, wherein similar reference characters are used to designate corresponding parts throughout the 35 several views:

Figure 1 is a reverse view of a button constructed substantially in accordance with this invention and drawn to a somewhat exaggerated scale.

Fig. 2 is a front view of the button as shown in Fig. 1, and

Fig. 3 is a central transverse section of said button.

The button is preferably made entirely of celluloid, or other similar material, and 45 comprises a rear member 1 having a flange 4 around its edge, and a front member 5 having a flange 6 overlapping and suitably secured to said flange 4 of the rear member,

as by cement, or the like. The rear member 1 has its central portion pressed out to form a shank 2 which is provided with openings 3 for the passage of thread used in attaching the button to a garment.

55

The front member 5 is formed with a recess 7 in its face, and in said recess is fitted a decorated panel 8 having an inwardly turned flange 9 at its edge to fit snugly within the walls of said recess. The panel may 60 be secured in place by any suitable means as by cement placed between the flange 9 and walls of the recess 7. The panel, when inserted in the recess, is preferably flush with the front surface of the button, but the 65 flange 9 and walls of the recess serve to strengthen and reinforce the button. To further reinforce the button structure the front member 5 may be corrugated, as at 10, 70 between the recess and marginal flange 6.

It will be understood that the panel 8 may be ornamented in any desired manner, the particular design 11, illustrated in Fig. 2, being simply shown by way of example. While the button illustrated is round, it is 75 obvious that it may be made in various other shapes without departing from the invention.

I claim:

1. The combination with a button having 80 a recess in its face with a surrounding wall extending substantially at right angles to its base, of a panel having a flange at its edge inwardly turned at right angles thereto and fitted in said recess, the outer face of 85 said flange engaging the inner face of said wall for the purpose specified.

2. The combination with a button having a recess in its face with a surrounding wall extending substantially at right angles to 90 its base, of a panel having a flange at its edge inwardly turned at right angles thereto and fitted in said recess, the outer face of 95 said flange engaging the inner face of said wall for the purpose specified, there being corrugations in the face of the button around the recess for the purpose specified.

In testimony whereof I have signed my name to this specification.

MARTIN PATREMIO.
